**DESIGN FOR A BASE FRAME FOR CHILD'S
ROCKING TOY OR SIMILAR ARTICLE**

**Leslie Peltier, Delphos, Ohio, assignor to The
Delphos Bending Company, Delphos, Ohio, a
corporation of Ohio**

Application March 26, 1940, Serial No. 91,264

Term of patent 14 years

To all whom it may concern:

Be it known that I, Leslie Peltier, a citizen of the United States, residing at Delphos, in the counties of Allen and Van Wert, State of Ohio, have invented a new, original, and ornamental Design for a Base Frame for Child's Rocking Toy or Similar Article, of which the following is a specification, reference being had to the accompanying drawing, forming a part thereof.

Fig. 1 is a perspective view of a base frame for child's rocking toy or similar article showing my new design; and

Fig. 2 is a side elevational view thereof.

I claim:

The ornamental design for a base frame for child's rocking toy or similar article, as shown.

LESLIE PELTIER.
